Specification for Design.

Patented July 5, 1921.

Application filed December 28, 1920. Serial No. 433,655. Term of patent 7 years.

To all whom it may concern:

Be it known that I, SAMUEL GAGE, a subject of the King of England, residing at 2 Middleton road, Holloway, London, N. 7, England, have invented a new, original, and ornamental Design for a Motor-Omnibus Body, of which the following is a specification, reference being had to the accompanying drawing, forming part thereof.

The figures are respectively a side per-

spective view, a back perspective view and a front perspective view of the motor omnibus body illustrating my new design.

I claim:

The ornamental design for a motor omnibus body as shown.

SAMUEL GAGE.
